UNITED STATES PATENT OFFICE.

HARLEY R. MARKEL, OF COLUMBUS, OHIO.

INSULATOR.

1,201,325.

Specification of Letters Patent. Patented Oct. 17, 1916.

Application filed December 26, 1913. Serial No. 808,869.

To all whom it may concern:

Be it known that I, HARLEY R. MARKEL, a citizen of the United States, residing at Columbus, in the county of Franklin and State 5 of Ohio, have invented certain new and useful Improvements in Insulators, of which the following is a specification.

My invention relates to insulators of the type used primarily in wiring a building and 10 adapted to support a wire a predetermined distance from an attaching wall.

To this end my invention aims to provide a simple and practical construction of insulator overcoming, to a marked degree, the 15 frailty usually found in a porcelain ware of this type. Also, I aim to provide a structure whereby the various sections comprising the insulator, as a whole, will be firmly held in their set position. In carrying forth this 20 idea, I have also endeavored to present a structure such that the various sections may be suitably supported while undergoing the glazing process, these supporting surfaces being so arranged that those surfaces normally exposed to view when the insulator is 25 in its position, will not be marred.

Other objects of my invention will be more apparent after a further detailed description of the accompanying drawings, in 30 which similar characters of reference designate corresponding parts and in which:

Figure 1 is a longitudinal vertical section of an insulator embodying the principles of my invention, Fig. 2 is a side elevation of the 35 structure shown in Fig. 1, Fig. 3 is an elevation of the structure shown in Fig. 2 but taken at right angles thereto, Fig. 4 is a transverse vertical section of my insulator, Fig. 5 is a view in perspective of one of the 40 members comprising my insulator, Fig. 6 is a view in perspective of the coöperating member used in connection with the structure shown in Fig. 5, and, Fig. 7 is a view in perspective of my assembled insulator.

In carrying forth my invention, I have provided what is known as a two-part insulator, these parts being designated by the numerals 1 and 2. Both the members 1 and 2 are centrally bored longitudinally, as 45 shown at 3 and 4, these bores being adapted to register to form an easy means of attachment with an attaching screw. The upper and lower walls may be countersunk, as shown at 5, or counterbored as shown at 6, 50 as may be desired, these features not being a part of the present invention.

In order to comply with the various laws regulating the mounting of conducting wires, I have provided the present insulator with one wire receiving groove only, this 60 groove being formed by the coöperation of the groove 7 formed in the member 2 and a coinciding groove 8 formed in the member 1. As will be seen by reference to the drawings, these grooves are disposed along one edge 65 of the insulator and considerably to one side of the longitudinal bores. In order that the two members may be securely held in their assembled positions, I have provided the upper member 2 with two spaced lugs 9 and 10, these lugs being at substantially right angles to the groove 7 and extending across the body portion of the member 2 its entire 70 width. Coöoperating with the spaced lugs 9 and 10, there is provided an upstanding centrally disposed lug 11, also substantially at right angles to the groove 8. This last mentioned lug is adapted to neatly fit the space between the lugs 9 and 10 and each of the lugs 9, 10 and 11 is provided with a plane-faced end wall as is indicated at 12. Further, the lower member of one or both 75 may also be provided with small projecting knobs as shown at 13. During the glazing process, the lower member may rest upon 80 these knobs permitting the entire surface of the remainder to be glazed, or it may rest on the end wall 12 of the lug 11 supplemented by the edges of the groove 8 while the upper member may rest upon the end walls of the 85 lugs 9 and 10, thereby marring only the surfaces hidden from view after the parts are 90 in their assembled condition.

In order to guard against any possible contact of the conducting wire with the attaching screw, I have provided the upper member 2 with an upwardly extending shoulder, as shown at 14, this shoulder being centrally disposed with relation to the longitudinal bore 3 and occupying a portion 95 of the spacing between the spaced lugs 9 and 10. The lower member 1 is complementally formed to receive this shoulder, in that a socket is provided by cutting away a portion of the upstanding lug 11, as shown 100 at 15. Therefore, when the two parts are in their assembled condition, the shoulder 14 will project upwardly a slight distance 105 to guard against all possible contact of the conducting wire with the metallic attaching screw.

From the above description, taken in con-

nection with the accompanying drawings, it will be apparent that I have provided a comparatively simple structure of insulator and one that will withstand the abuses 5 heaped upon this ware during shipment. Ordinarily, the weakest point of an insulator is from the wire receiving groove on a diagonal line to the top wall where this wall is braced for the attaching screw. 10 Also, all projecting formations are frequently broken. By disposing the wire receiving groove to one side, as shown, the projecting shoulder 14 gives added strength to this part to prevent cracking as well as 15 preventing engagement of the conducting wire with the attaching screw. Also, by this structure, all projecting lugs may be made sufficiently heavy to guard against all breakage.

20 What I claim, is:

1. A two part insulator comprising complementary members adapted for superimposition, said members being longitudinally bored for an attaching screw and each provided with a wire receiving groove, a lug on one of said members having a plane faced portion on a level with at least one edge portion of the groove in the same member, 25 said lug extending laterally in a direction substantially at right angles to its groove across said member the remainder of its width, and a complementary lug having a plane faced portion on the other of said complementary members substantially at 30 right angles to its wire groove and continuing from said last named groove across said member its full width.
2. A two part insulator comprising complementary members adapted for superimposition, said members being longitudinally bored for an attaching screw and each provided with a wire receiving groove, a lug on one of said members having a plane faced portion on a level with at least one edge portion of the groove in the same member, 45 said lug extending laterally in a direction substantially at right angles to its groove across said member the remainder of its width, spaced lugs on the other of said members arranged to straddle said first named lug, said spaced lugs having flat ends and being disposed substantially at right angles to the wire groove in said last named member and extending from its groove across the remainder of the width of said member. 50
3. A two part insulator comprising complementary members adapted for superimposition, said members being longitudinally bored for an attaching screw and being each provided with a single wire receiving groove 60 disposed to one side of said bores, spaced lugs having plane faced ends on one of said members substantially at right angles to its wire groove and extending across the body portion of the member the remainder of 65 its width, a projecting shoulder in the space between said lugs through which the longitudinal bore is adapted to pass, and a complementary lug on the other member disposed substantially at right angles to its 70 wire groove and extending from the groove across the body portion of the member the remainder of its width, said last named lug being adapted to fit the space between said first named lugs and being also provided 75 with a socket to receive said shoulder on the other member.

In testimony whereof I affix my signature in presence of a witness.

HARLEY R. MARKEL.
